STREET CAR SIGN

Filed Nov. 30, 1928

Fig. 4.

By his Attorney

Maurin Rein

UNITED STATES PATENT OFFICE

KARL KLUG, OF BROOKLYN, NEW YORK

STREET CAR SIGN

Application filed November 30, 1928. Serial No. 322,766.

This invention relates to signs and more particularly to apparatus for automatically displaying signs on street cars.

As is well known, it is usually the duty of street car attendants to call out the various streets which the car crosses during its journey. During the rush hours it is very inconvenient, and often impossible for the attendant to give his attention to his more important duties and at the same time call out the various streets.

It is, therefore, an object of this invention to provide an apparatus for automatically displaying the name of the street which the car will next cross, and also the name of the next two succeeding streets.

It is a further object of the invention to provide an automatic sign apparatus which may readily be installed in the standard street car without material alteration.

These and other objects are attained by the novel construction, combination and arrangement of parts hereinafter described and shown in the accompanying drawings constituting a material part of this disclosure and in which:

Figure 1 is a plan view of the sign apparatus.

Figure 2 is a view taken on line 2—2 of Fig. 1.

Fig. 3 is a diagrammatic view of the wiring connections.

Fig. 4 shows in side elevation and section on line A—A respectively the construction of the solenoid in detail.

Referring to Figure 1, a casing 3 is provided with a front wall 4 having an aperture 5, which is covered by a transparent glass pane 6.

Rotatably mounted on a side wall of the casing are a pair of pulleys 7 and 8, over which pass a strip 9, upon which is mounted a plurality of stencilled signs, such as shown at 10, 11 and 12, the last mentioned signs as shown, being visible through the aperture 5. Sign 11 may show the next street to be crossed, while signs 10 and 12 may show the two adjacent streets.

The strip 9 has its ends attached to drums 13 and 17, the strip being wound or unwound

from the drums depending upon the direction in which the car is traveling.

Drum 13 is fixed to a shaft 14, to which is fixed a disc 15 having a plurality of laterally projecting pins 16 near its periphery. The drum 17 is similarly mounted on a shaft 18, to which is fixed a similar disc 19 also provided with laterally projecting pins 20.

Fixed to shaft 18 is a ratchet wheel 21 engaged by a pawl 22 forming one arm of a pivoted lever 23, the latter being connected by a link 24 to a lever 25, having a pawl 26 on one end, the pawl 26 engaging a ratchet wheel 27 fixed to shaft 14. The teeth of ratchet wheel 27 are reversely directed to the teeth on wheel 21.

A dog 28 lies in the path of pins 16, the lug being freely movable in a clockwise direction but limited in movement in a counter-clockwise direction by the end of a slot 29 in a casing having a solenoid 30 wound thereabout for giving the core its initial movement to bring the same into the sphere of influence of electromagnet 32 or 33.

The dog 28 is pivoted to an arm 31' of a plunger 31 slidable in the solenoid casing, and adapted to be attracted by either of two electromagnets 32 and 33 mounted on the walls of casing 3, the solenoids of the magnets being energized at the proper times by electrical connections under the control of the motorman of the street car.

A similar structure including a dog 34, plunger 35 and electromagnets 36, 37 is provided for the drum 17. Dogs 28 and 34 are each provided with a shoulder allowing the swinging of the dogs in one direction only i. e. a direction to turn of their respective discs.

In operation, when the motorman desires to shift the signs the solenoid 32 is energized to pull the plunger 31 towards it, which movement of the plunger causes the dog 28 to rotate the disc 15 by bearing against one of the pins 16, at the same time pawl 26 is cammed upwards to cause the lever arm 25 to move in a downward direction to release pawl 22 from engagement with ratchet wheel 21, thus allowing the strip to be unwound from the drums 17 and wound upon the drum 13. The

strip is thus moved a sufficient distance to indicate the desired street, and inasmuch as it is customary for a motorman to throw off his motor upon approaching each street crossing, electrical connections may be provided so that the apparatus will be operated whenever the motorman disconnects the motor when approaching a street crossing. The plunger 31 is returned to its initial position 10 by the pull of electromagnet 33 which is energized by a separate connection when the motor is thrown into operation again.

When the end of the line has been reached the apparatus is reversed so that the strip 15 will be wound upon drum 17 and unwound from drum 13.

From the above description it will be seen that there has been provided a simple and convenient sign apparatus especially adapted 20 for indicating the streets traversed by a street car during its travel.

The foregoing disclosure is to be regarded as descriptive and illustrative only, and not as restrictive and limitative of the invention, 25 of which obviously an embodiment may be constructed including many modifications without departing from the general scope herein indicated and denoted in the appended claims.

30 Having thus described my invention, what I claim as new and desire to secure by Letters Patent, is:

1. An apparatus for indicating streets crossed by a street car, comprising a casing, 35 a strip, a pair of drums to which the ends of the strip are attached, a plurality of signs on the strip, a pair of shafts to which the drums are fixed, ratchet wheels fixed to the shafts, discs fixed to the shafts, said discs 40 having a plurality of laterally projecting pins, pawls engaging the ratchet wheels, dogs adapted to engage the pins on the discs to rotate the latter and electromagnetic means to move the dogs in one direction.

45 2. In a sign apparatus, a drum, a strip having one end attached to the drum, a shaft upon which the drum is fixedly mounted, a disc fixed to the shaft, a plurality of pins projecting laterally from the disc, a dog 50 adapted to engage the pins, a plunger upon which the dog is pivotally mounted, a second drum to which the other end of the strip is attached, a pawl and ratchet means to prevent accidental rotation of the drums, and 55 electromagnetic means to pull the plunger in one direction to cause the dog to rotate the disc and disengage the pawl and ratchet means so that the strip may be wound upon the first mentioned drum.

60 In witness whereof I affix my signature.
KARL KLUG.
